UNITED STATES PATENT OFFICE.

ROBERT C. EDWARDS, OF ELIZABETH, NEW JERSEY, ASSIGNOR TO RADIO CORPORATION OF AMERICA, A CORPORATION OF DELAWARE.

DESIGN FOR A GRILLE FOR RADIOCABINET OR SIMILAR ARTICLE.

Application filed July 19, 1924. Serial No. 10,195. Term of patent 14 years.

To all whom it may concern:

Be it known that I, ROBERT C. EDWARDS, a citizen of the United States, and resident of Elizabeth, New Jersey, in the county of Union and State of New Jersey, have invented a new, original, and ornamental Design for Grille for Radiocabinet or Similar Article, of which the following is a specification, reference being had to the accompanying drawing, forming part thereof.

The single figure of the drawing is a front view of a grille, showing the new design.

The grille of the invention is particularly intended and adapted for use with a loud speaker or like acoustical horn enclosed in a cabinet and is placed over the mouth of the horn.

I claim:

The ornamental design for a grille for radio cabinet or similar article as shown.

ROBT. C. EDWARDS.
